[57] CLAIM

The design for a reversible baffle, as shown and described.

DESCRIPTION

FIG. 1 is a perspective view taken from the top, front and one side of a reversible baffle embodying my new design;

FIG. 2 is a front elevational view thereof;

FIG. 3 is an elevational view taken from one side thereof, the opposite side being the same as the side shown;

FIG. 4 is a rear elevational view thereof;

FIG. 5 is a bottom plan view thereof; and

FIG. 6 is a top plan view thereof.

FIG. 1

FIG. 2

FIG. 3

FIG. 4

FIG. 5

FIG. 6
